VULCANIZER

Leo J. Larkin, John J. Regan, and Gerald A. Larkin, La Crosse, Wis., assignors to La Crosse Rubber Mills Company, La Crosse, Wis., a corporation of Wisconsin

Application April 19, 1946, Serial No. 663,394

5 Claims. (Cl. 18—6)

1

The invention relates to a vulcanizer of the general type in which cars supporting footwear or other articles to be cured, are confined in a horizontally elongated casing in which air under pressure is heated to a vulcanizing temperature and circulated.

Heretofore, it has been practically impossible to uniformly heat and circulate the air throughout the length of vulcanizers of the above mentioned type, resulting in non-uniform vulcanizing, but the present invention has effectively overcome this difficulty.

Figs. 1 and 1a of the accompanying drawings jointly disclose a substantially central, vertical, longitudinal, sectional view through the improved vulcanizer.

Figs. 2 and 3 are transverse sectional views on lines 2—2 and 3—3 of Fig. 1.

The general construction shown in the drawings may be considered as preferred and while that construction will be rather specifically described, attention is invited to the possibility of making variations within the scope of the invention as claimed.

A horizontally elongated cylindrical casing 5, is provided, said casing having a head 6 at its rear end and a suitably operated door 7 at its front end. Heat insulation has been shown at 8 on the head 6 and door 7 and may well be used throughout if desired. For later reference, the casing top is denoted at 9, the opposed substantially vertical side walls at 10, and the bottom at 11. Suitable rails 12 are secured upon the bottom 11 to support the cars (not shown) upon which the articles to be vulcanized, are supported.

A transversely arched inner wall 13 is suitably secured in the casing 5 and extends substantially throughout the length thereof, said arched inner wall 13 having a preferably flat top portion 14 spaced downwardly from the casing top 9, and substantially vertical side portions extending downwardly from said top portion 14 and spaced inwardly from the opposed casing sides 10. In the present disclosure, these side portions of the arched inner wall 13 are formed of upper, intermediate and lower sections 15, 16 and 17 suitably secured together, the lower edges 18 of the sections 17 being spaced above the casing bottom 11. The arched inner wall 13 thus contacts with the casing top 9 and side walls 10 in forming a transversely arched chamber 19, the lower portions of which communicate at 20 with the space 21 within the confines of said arched inner wall 13. Openings 22 are formed through longitudinally spaced portions of the inner wall top 14 and place the upper portion of the arched chamber 19 in communication with the upper portion of the space 21, and blowers 23 are provided in said chamber 19 over said openings 20.

2

for transversely circulating the air as indicated by the arrows.

Longitudinal, air-heating, steam coils 24 are provided in the arched chamber 19 between the casing side walls 10 and the sections 16 of the arched inner wall 13, and said coils are provided with heat-radiating fins 25 secured to said sections 16. Heating coil units of the fin-type shown are customarily manufactured with longitudinal side plates, and we simply utilize these side plates to form the sections 16 of the arched inner wall 13. There are two of these heating units at each side of the vulcanizer in the construction shown, and the ends of said units are spaced apart to facilitate installation of the necessary fittings. To prevent any of the circulated air from passing between the units instead of through them, suitable baffles 26 are employed. Other baffles prevent the air from passing behind the rear ends of the rear coils, one of these baffles being shown at 27 in Fig. 1a.

Transverse arched partitions 28 are provided in the arched chamber 19 between the openings 22 and thus allot a predetermined portion of the air to each blower so that better circulation will result. These partitions 28 extend from the heating coils at one side of the casing to those at the other side but none are necessary below these heating coils. The partitions 28 may be welded or otherwise secured to the casing 5 and the upper sections 15 of the inner wall 13, as well as the top 14, may be flanged at 29 and secured to the inner edges of said partitions.

The front and rear ends of the upper portion of the arched chamber 19 communicate at 30 with the end portions of the casing 5, and transverse fin-type steam coils 31 are mounted in said ends to heat the air which is downwardly circulated in said casing ends as indicated by the arrows. From the ends of the coils 31 to the level of the coils 24, the front and rear ends of the chamber 19 are closed by plates 32. Were it not for the heaters 31, the zones within the end portions of the casing 5 (including the outer end portions of the endmost of the spaces 21) would be cooler than the rest of said spaces 21. This is due to the fact that there is considerable added metal in the end enclosure 6 and door 7 and considerable heat losses from said added metal, even though insulated. The heaters 31 are so sized and rated as to merely compensate for these heat losses without overheating the aforesaid zones.

Suitable provision may be made for injecting air under desired pressure into the casing, and the pipe 33 of Fig. 1a may be considered as for this purpose. Then too, any instruments necessary for temperature control, pressure control, etc., may be connected with the casing in any suitable ways forming no parts of the present invention.

It will be seen from the foregoing that the vulcanizing air will be substantially uniformly heated and circulated and there will thus be no zones of widely varying temperatures as heretofore, making much better results possible.

Attention is again invited to the possibility of making variations within the scope of the invention as claimed.

What is claimed is:

1. A vulcanizer comprising a horizontally elongated closed casing having a door at one end; a transversely arched inner wall extending substantially throughout the length of said casing, said transversely arched inner wall having a top portion spaced downwardly from the top of said casing, and substantially vertical side portions extending downwardly from said top portion and spaced inwardly from opposed side walls of said casing, said transversely arched inner wall coacting with said casing top and side walls in forming a transversely arched air chamber, said side portions of said transversely arched inner wall having lower edges spaced upwardly from the casing bottom to place the lower portions of said transversely arched chamber in communication with the space within the confines of said transversely arched inner wall, said top portion of said transversely arched inner wall having longitudinally spaced openings placing the upper portion of said transversely arched chamber in communication with said space; air blowing means adjacent each of said openings for causing flow of air therethrough in one direction to transversely circulate the air in said casing and said transversely arched chamber, air heaters in said transversely arched chamber for heating the circulated air, and transverse partitions in said transversely arched chamber between said longitudinally spaced openings and segregating the air blowing means of these openings from each other.

2. A structure as specified in claim 1; the ends of said upper portion of said transversely arched chamber being in communication with the end portions of said casing, and air heaters in said ends of said upper portion of said transversely arched chamber.

3. A vulcanizer comprising a horizontally elongated closed casing having a door at one end; a transversely arched inner wall extending substantially throughout the length of said casing, said transversely arched inner wall having a top portion spaced downwardly from the top of said casing, and substantially vertical side portions extending downwardly from said top portion and spaced inwardly from opposed side walls of said casing, said transversely arched inner wall coacting with said casing top and side walls in forming a transversely arched air chamber, said side portions of said transversely arched inner wall having lower edges spaced upwardly from the casing bottom to place the lower portions of said transversely arched chamber in communication with the space within the confines of said transversely arched inner wall, said top portion of said transversely arched inner wall having longitudinally spaced openings placing the upper portion of said transversely arched chamber in communication with said space; air blowing means adjacent each of said openings for causing flow of air therethrough in one direction to transversely circulate the air in said casing and said transversely arched chamber, horizontally elongated air-heating coils disposed longitudinally in said transversely arched chamber between said side portions of said transversely arched inner wall and said opposed side walls of said casing; transverse partitions in said transversely arched chamber between said longitudinally spaced openings and segregating the air blowing means of these openings from each other, said transversely arched partitions extending downwardly to said air-heating coils; additional horizontally elongated air-heating coils disposed transversely in the ends of said upper portion of said transversely arched chamber, said ends being in communication with the end portions of said casing; and plates extending from the ends of said additional coils and partially closing the front and rear ends of said transversely arched chamber.

posed side walls of said casing, and transverse partitions in said transversely arched chamber between said longitudinally spaced openings and segregating the air heating means of these openings from each other.

4. A structure as specified in claim 2; the ends of said upper portion of said transversely arched chamber being in communication with the end portions of said casing, and horizontally elongated air heating coils disposed transversely in said ends of said upper portion of said transversely arched chamber.

5. A vulcanizer comprising a horizontally elongated closed casing having a door at one end; a transversely arched inner wall extending substantially throughout the length of said casing, said transversely arched inner wall having a top portion spaced downwardly from the top of said casing, and substantially vertical side portions extending downwardly from said top portion and spaced inwardly from opposed side walls of said casing, said transversely arched inner wall coacting with said casing top and side walls in forming a transversely arched air chamber, said side portions of said transversely arched inner wall having lower edges spaced upwardly from the casing bottom to place the lower portions of said transversely arched chamber in communication with the space within the confines of said transversely arched inner wall, said top portion of said transversely arched inner wall having longitudinally spaced openings placing the upper portion of said transversely arched chamber in communication with said space; air blowing means adjacent each of said openings for causing flow of air therethrough in one direction to transversely circulate the air in said casing and said transversely arched chamber, horizontally elongated air-heating coils disposed longitudinally in said transversely arched chamber between said side portions of said transversely arched inner wall and said opposed side walls of said casing; transverse partitions in said transversely arched chamber between said longitudinally spaced openings and segregating the air blowing means of these openings from each other, said transversely arched partitions extending downwardly to said air-heating coils; additional horizontally elongated air-heating coils disposed transversely in the ends of said upper portion of said transversely arched chamber, said ends being in communication with the end portions of said casing; and plates extending from the ends of said additional coils and partially closing the front and rear ends of said transversely arched chamber.
